UNITED STATES PATENT OFFICE.

JOSEPH E. GADBOIS, OF SPRINGFIELD, MASSACHUSETTS.

BUTTON-SEWING MACHINE.

1,162,471.

Specification of Letters Patent.

Patented Nov. 30, 1915.

Application filed January 7, 1914. Serial No. 810,894.

To all whom it may concern:

Be it known that I, JOSEPH E. GADBOIS, a citizen of the United States of America, and resident of Springfield, in the county of Hampden and State of Massachusetts, have invented certain new and useful Improvements in Button-Sewing Machines, of which the following is a full, clear, and exact description.

10 This invention relates to a machine for the sewing of buttons, having eye perforations, on fabric; and it is advantageously operative, by reason of its duplicated or plural mechanisms, for simultaneously sewing several buttons onto the fabric.

15 The machine is one comprising means for guiding buttons to a position in relation to a feeder, a "finder" or device for engagement in the diametrically opposite eyes of the button which is operative to rotatively move the button so that the opposite eyes thereof will be in a line longitudinally of the machine, that is one extending from the front to the rear; actuating mechanism operating the 20 feed slide to transfer the eye positioned button forwardly into the presser foot which is constructed for the reception and retention thereof; an organization of the sewing machine whereby the presser foot (capable of a 25 rising and lowering motion for clamping and disengaging the fabric) together with the throat plate are reciprocated within a short range of movement in the longitudinal line of the machine so that the button is successively shifted during the sewing operation to bring the opposite eyes thereof alternately coincident with the axial line of the needle carried by the vertically reciprocatory needle bar. Furthermore, the organization 30 of the machine is such that the button finder, and button transferring devices have their operations in their own time, while the sewing mechanism is idle, and vice versa,—the driving mechanisms for the devices operative 35 on the button and the button sewing mechanism having means for their control which are highly important in contributing to the successful automatic action of the machine; and the machine, moreover, includes 40 an automatically operative device for severing the threads between the needle and shuttle, beneath the fabric, and below the throat plate so that after the button has been sewed onto the fabric and coincident with 45 the starting of the mechanism which feeds the next button into the presser foot, the

fabric with the button sewed thereon may be withdrawn from its position between the throat plate and presser foot, without drawing out any of the needle thread and shuttle 60 thread therewith.

The invention is described in conjunction with the accompanying drawings and is set forth in the claims.

In the drawings:—Figure 1 is a plan view 65 of the machine shown as of duplex character, that is having mechanisms for the sewing onto the fabric of two buttons simultaneously. Fig. 2 is a side elevation of the machine; Fig. 2^a is a detail plan view showing the separable character of the button receiving presser foot. Fig. 3 is a longitudinal vertical sectional view on line 3—3, Fig. 1. Fig. 4 is a partial longitudinal vertical sectional view on line 4—4, Fig. 1. Fig. 5 70 is a vertical cross sectional view on line 5—5, Fig. 3, as seen looking in the direction of the arrow. Fig. 6 is a partial vertical sectional view on a plane transversely of the machine as taken on line 6—6, Fig. 3,—the same particularly showing the button-hole finder. Fig. 7 is a view longitudinally of the machine and at right angles to Fig. 6, showing 75 the finder as having engaged and positioned the button with its opposite eyes alined with the presser foot. Fig. 8 is a view similar to Fig. 7, but showing the finder as having been retired downwardly and the button as having been fed forwardly into the presser foot. Fig. 9 is an inverted plan view of the 80 machine. Fig. 10 is a perspective view showing constructions for interengagements between the pulleys employed for actuating the sewing mechanism and the button positioning and feeding. Fig. 11 is a side view 85 to show the adjustable capability of the crank pin which longitudinally shifts the presser foot and throat plate.

For brevity and the avoidance of confusion, the description will be mostly confined to an organization comprising a single button-controlling mechanism and a single button-sewing-on mechanism, and the thread severing device therefor.

In the drawings, A represents the table of 105 the machine, B representing one of the goose-neck standards thereon.

C represents the throat plate, D the needle bar, carrying the vertical needle *a* as usual to which the needle thread *x* is supplied as 110 usual, and E represents the rotary shuttle, the sewing mechanism including the needle,

and shuttle, which I have employed, being of the Singer type.

F represents the presser foot which is capable of being lifted and lowered to disengage and clamp the fabric and when lifted to have a position at the level and just forward of the button guide b down to which the laterally disposed oblique button-feed chute c leads.

10 The pulley on the sleeve shaft G² drives the sewing portion of the machine, that is needle bar and shuttle and causes the back and forth reciprocation of the presser foot and throat plate in unison; while the pulley H on the shaft H² actuates the shaft J having cams and other appliances thereon which actuate the button-finder, and button-feeding or transferring device and controls the belt shifter K for the belt L which alternately drives the pulleys G and H; and one of which cams on such cam shaft J automatically causes the stopping of the machine after a button has been sewed onto the fabric. The shaft H² when driven by the belt and pulley, drives the cam shaft J through the spiral gear wheels H³ and H⁴, the horizontal shaft H⁵, the pinion H⁶ on the shaft H⁵ and the gear wheel J² on the cam shaft.

30 The sewing machine shaft B² is driven from the sleeve shaft by means of spiral gears G³, G⁴, seen in Fig. 4, the latter gear G⁴ being on a horizontal shaft G⁵ which extends to within the goose-neck standard B and has connection by bevel gear wheels G⁶ and G⁷, with a vertical shaft G⁸ which shaft through the bevel gear wheels G⁹ and G¹⁰ has connection with the shaft B² which operates the needle bar D, and the thread take-up in the usual manner; and the said vertical shaft G⁸ through the bevel gears G¹² and G¹³, drives the shuttle shaft E².

45 The buttons are loaded into the oblique chute c and by gravity settle in the receiver b provided therefor and formed as a short horizontal continuation of the chutes slightly above the level of the table A. Co-acting with the receiver is the finder, here shown as consisting of a disk e having a 50 pair of upstanding diametrically opposite small pins e² spaced corresponding to the separation of the eye holes of the button, and an axially rotative vertical shaft e³ on the upper end of which the finder is carried. The finder also has combined therewith a yoke of light construction, into 55 which the button coming from the chute into the button receiver b is temporarily pocketed or trapped, to be held against any such placement in a line fore and aft of the machine as would prevent the proper registration and engagement of the finder pin in the buttonholes. This yoke represented by f, in 60 practice is made of a rectangular sheet metal blank having the opposite extremities

thereof bent upwardly at right angles to the base portion which is engaged, under the head of the finder, with the carrying shaft e³.

65 K represents the transferring slide behind the button receiver and finder and in the line of the presser foot which is made of such channeled or apertured construction as to permit the reception and engagement of the button when the latter is forwardly forced by the slide from the receiver into such presser foot.

70 The shaft or spindle, carrying the finder, is mounted and guided for a vertical up and down motion; and it has rotary motion imparted to it, so long as it is permitted to turn, by means of the small driving band e⁴ which is driven from the pulley e⁵ on the shaft J and around the grooved pulley e⁶ affixed on the vertical shaft e³.

75 At a suitable time in the operation of the machine after the button has been fed to position in the yoke f within the receiver b, the revolving finder shaft is permitted to rise under the reaction of its elevating spring e⁷, until its pins e² strike against the bottom of the button, which button is resisted in an upward direction by the inturned ledges or flanges b³ at the top of the receiver; and then, so soon as the pins engage in the buttonholes, the line intersecting both of which may be in any direction, as the buttons come into the receiver at random, the finder moving still farther upwardly for such engagement, the buttons are rotated just far enough to align the buttons truly in the fore and aft line of the machine, which, accomplished, the further rotary motion of the upright shaft and the finder is arrested by the engagement of the stop lug e⁸ on the upper side of the pulley e⁶ with a shoulder g² of a sleeve g, which surrounds an intermediate part of the shaft e³ and through which said shaft is freely rotatable; but the said sleeve is non-rotative, but is capable of a slight degree of vertical movement, it being under the reaction in an upward direction of the spring g³ and caused to have its lowering movement by the engagement therewith of a

80 bent arm g⁴ which is carried as an upper end extension of a bar g⁵, and which bar has a lug or short arm g⁶ at its lower end in position to be engaged by the approximately horizontal lever h fulcrumed at h² beneath the table, and subjected to the crowding action of the cam i at the lower end of a lever i², which lever coacts with the button transfer slide K.

85 The lever i², with the cam i, is affixed on a rockshaft i³, indicated in Figs. 2, 3, 7, 8 and 9; and the rocking motion of such shaft to impart the swinging motion to the slide operating lever and to the finder depressing lever, whereby the latter will be lowered and disengaged from the button just previous to

80

130

the time when the slide forwardly pushes the button into the presser foot, is accomplished by a thrust rod i^4 , horizontally slid-able, adapted to engage a fixed upstanding arm i^5 of the rockshaft and to receive its thrust motion by the wiper cam i^6 revolvably carried by the cam shaft J; and after the wiper cam has passed around clear from engagement with the thrust rod, the latter is then free to have its quick retracting move-ment from the power of the spring i^7 having connection with a fixed depending arm i^8 of the rockshaft and an anchorage at the under side of the table, see Figs. 2 and 9.

15 The sleeve g which is vertically movable and more or less in conjunction with the vertical movements of the upright shaft e^3 is formed with a spline rib g^7 which engages in a groove or notch therefor in the bracket g^8 .

20 Assuming that the parts are in the rela-tions shown in Fig. 8, that is, the lever arm i^2 after having been swung farther to the leftward, to place the button with an eye thereof in alinement with the needle a , is 25 retiring to the rightward to withdraw the transfer slide K to its normal position to bring its left hand end to the position shown in Fig. 7.

The formation of the cam end i of the 30 lever i^2 is such that the horizontal lever h is not released for its maximum upward throw until an instant after the working end of the slide is carried beyond the line of the feed of the button to the chute so that a but-ton will surely come into the chute before the upwardly spring pressed parts e and g 35 may move to the extent of their capabili-ties.

The driving pulley e^6 for the finder shaft e^2 therefore remains locked to the sleeve during the greater portion of a cycle of the ma-chine; but as will be perceived in Fig. 6, when the lever h and the connections g^6 , g^5 and g^4 between it and the sleeve permit the 45 sleeve to move upwardly to its limit under its spring g^3 , the finder and its shaft will first move upwardly a little less far because its pins will strike against the bottom of a button at non-perforated parts thereof; and 50 thus there will be a disconnection between the pulley e^6 and its sleeve, as shown in Fig. 6, to permit the driving band to cause the rotation of the finder shaft pulley for the 55 operation of the finder; but this operation can only continue after the finder pins have engaged in the button for so much of a revo-lution as is necessary for the alinement of the button holes because the stop lug e^8 is so positioned with relation to the line extend-ing between the finder pins that when the latter have been revolved sufficiently to prop-erly position the button, the reengagement 60 between the pulley and the sleeve will take place.

65 The important object of the provision of

the vertically movable but non-rotative sleeve g in conjunction with the finder shaft and its pulley e^6 which is adapted for the interlocking with the sleeve as described, is that the rotation of the finder shaft while 70 it is descending to carry its pins out of en-gagement with the properly alined button holes must be absolutely prevented, for should the catch lug of the finder shaft pul-ley become disengaged from its stop before 75 the finder pins are lowered entirely out of the eyes of the button, the button after hav-ing been properly positioned would be ro-tatively displaced from such position, thus 80 destroying the practicability of the device; 85 but as will be perceived on reference espe-cially to the sectional views, Figs. 6, 7 and 8, the finder shaft is in clutch with the sleeve in both the lowered and spring lifted posi-tions of the latter and is only out of clutch 90 so that the finder can turn during the in-terval necessary for the pins to enter the button holes and to then turn the button around, as great or small a fraction of a revolution as is necessary to bring the but-ton holes to the proper alinement.

It is to be understood that during a con-siderable time the driving band running 95 around the pulleys on the cam shaft and on the upright finder shaft will slip on such pulleys.

The presser foot is carried at the extrem-ity of a return bent flat spring F^2 , the rear portion of which is secured to a horizontal slide P guided within the hollow goose neck 100 whereby, because of the resiliency of such spring the presser foot may have a substan-tially vertical movement so that it may be alternately raised to the level of, and to be 105 in alinement with, the button receiver and transfer slide K and to be lowered to clamp the fabric between it and the throat plate.

The means controlling the rising and fall-ing movements of the presser foot (seen in 110 Figs. 1, 2 and 9) consist in a vertically guided bar m on the side of the goose neck and to the angularly turned lower extremity m^2 of which the lower portion of the presser foot carrying the spring is connected; the intermediately fulcrumed lever m^3 and the 115 vertical thrust rod m^4 having at its lower end a yoke m^5 which embraces and is subject to the up and down moving action of the cam m^6 on the shaft J.

The aforementioned slide P guided in a 120 slideway P^2 therefor in the goose neck, shown in Fig. 3, and to which the presser foot carrying spring is connected, has re-ciprocatory movement for changing the po-sition of the button so that the eyes thereof 125 will be alternately coincident with the line of movement of the needle imparted thereto by a pitman rod n which is connected to the slide and to a crank pin n^2 carried on the face of a gear wheel n^3 mounted in an inter- 130

mediate part of the goose neck and in mesh with which is a gear wheel n^4 on the sewing machine shaft B^2 .

The presser foot F, as represented in Fig. 5 2^a, is made with opposite jaws o^1 o^2 pivoted at o^2 o^2 at a thickened or reinforced part of the presser foot carrying spring F², these jaws being normally held in approached relations by the spring o³; and the inner 10 edges of these separable jaws are suitably channeled or recessed for the reception therein of a button transferred thereinto by the feed mechanism.

After the button shall have been sewed 15 onto the fabric and the sewing thread cut, upon the withdrawal of the fabric in a forward direction, the buttons will be dragged out forwardly from within the presser foot; and the making of the opposite 20 portions of the presser foot of yielding members as stated, adapts such presser foot to the reception and retention therewithin of buttons which may slightly vary as to diameter.

25 The throat plate C, as indicated in Figs. 3 and 9, has in addition to the forward end portion which is above the table a downwardly offset and rearwardly extended portion C², to which reciprocatory movement 30 in the fore and aft line of the machine in unison with the presser foot is imparted by means of the pitman rod C¹ connected to the crank stud of the wheel n³ and having connection with the upper end of an inter- 35 mediately pivoted vertical lever C⁴, the pivot being represented by C⁷ in Fig. 3, which at its lower end has connection with one end of a transverse horizontal lever C⁵ intermediately pivoted under the table, the 40 other end of which is pivoted to the throat plate extension.

Suitable means for the guidance of the throat plates are provided; and in Fig. 9 it is seen that a pair of throat plates for the 45 duplicated machines are formed from a single plate.

Means are provided for the driving of the mechanisms or devices of this machine which are of a somewhat peculiar character, 50 inasmuch as in one complete operation of the machine between the time it is started and the time it is automatically stopped, the pulley G which drives the sewing mechanism is rotated for something like a half or 55 other fraction of the time of the cycle, while the pulley H which actuates the cam shaft J has its rotation during the complete cycle of operation of the machine, that is during the time in which the wheel J² and shaft J 60 make one complete rotation.

M represents a rod horizontally and longitudinally ranging under the table and formed with a catch shoulder s on its under side. This rod has a spring s² applied thereto for forcing it in a rearward direction,

and at its rear end it has an angular and upturned extension s³ extending into proximity to the forward face of the pulley G and provided with a belt shifter K. Also located beneath the table is a slid able horizontal longitudinal bar or rod Q having a catch shoulder q having the spring q² so applied thereto as to force the bar Q forwardly and provided with a transverse extension q³ terminating in an upward angular extension q⁴ in suitable proximity to the rearward face of the pulley H.

The pulley G has an internal face-ratchet surface t indicated in Figs. 4 and 10 of the drawing, with a shoulder t², and such pulley also has on its outer forward face a stop projection t³.

The pulley H which is made hollow or cup-shaped has therewithin the forwardly spring pressed stud u to be engaged, when the pulley G is rotated, by the belt by the shoulder t² at the end of the ratchet-like surface within the pulley G; and the opposite or rear end of this stud projects outwardly beyond the face of the pulley H.

90 The shoulder q of the rod Q is engaged when such rod is forced against its spring q² in a rightward direction by a transverse intermediately pivoted spring pressed latch lever R (see Figs. 5 and 9); and the shoulder s of the rod M moved forwardly against the spring is engaged by the transverse intermediately pivoted spring pressed latch lever S; and coacting with the ends of these levers which are opposite their shoulder-engaging portions are cams S² and R² on the shaft J.

The rods Q and M are set in their latched positions by the starting lever T (see Fig. 9) provided on the under side of the table 105 pivoted at T² connected by longitudinal rod T³ with an intermediately pivoted angular lever P⁴, all so arranged that a forward swinging of the free end of lever T will cause, through said connections, the forward 110 forcing of rod M and the rearward forcing of rod Q with their extensions.

In the starting of the machine the forward forcing of rod M places the belt on the pulley G, causing the driving of the parts 115 appurtenant to the sewing actions and at the same time causing the rotation of the pulley H which drives the cam shaft which, for the most part, pertains to the button feeding operations. The pulley H is driven 120 from the pulley G by its shoulder t² engaging the inner end of the spring pressed stud u.

The cam S² is so positioned or timed on the cam shaft that after the sewing mechanism has been operated for sewing on the button, it will trip the latch lever S and permit the rod M to be moved rearwardly under the force of its spring s² to shift the belt L off from pulley G onto pulley H, and 130

at the same time to carry the extension S^3 of such rod M which is just forward of the pulley G rearwardly far enough to be in the path of, and to intercept, the projection q^4 on the pulley G, causing the positive stoppage of the latter. The belt now being upon the pulley H causes the running of the latter in the same direction which it had been running, its spring stud now revolvably clicking 10 past the ratchet shaped surface in the pulley G. This further driving of the cam shaft J by the continued running of the pulley H will be until the shaft J has made a complete revolution, whereupon the cam R^2 will trip the latch lever R and liberate the rod Q, which being spring pressed in the forward direction will bring its extension q^4 into the path of, and to intercept the outward extension of the stud u and stop 15 the further driving of any of the mechanism of the machine until there is re-starting through the operation of the starting lever T.

The driving belt L when transferred onto 20 the pulley H, and after such pulley has been stopped by the intercepting part q^4 will slip on the pulley H until such time as in the ext starting of the machine it is shifted to run around on and drive the pulley G and 25 the mechanisms actuated thereby. Concurrently with the shifting of the belt from pulley G to pulley H, at the time when the sewing operation has been completed and the sewing mechanism remains idle, the end- 30 wise motion in the rearward direction of the rod M is effective for the operation of the shears which sever the sewing thread beneath the throat plate.

In Fig. 9, w represents a fixed shear member located in a horizontal plane under, and supported by, the table and having in no way any connection or coaction with the throat plate, such shear member being located in suitable proximity to the line of 45 stitching between the shuttle and the needle; and w^2 represents the pivotally mounted movable lever-like member of the shear,—the arm w^3 thereof oppositely from the cutting member and beyond the pivot being 50 pivotally connected to a rod or plate M^3 , the rearward extension of which latter comprises the belt shifter K.

It is to be explained that while the shaft J makes a complete revolution in one entire 55 operation of the whole machine, the cams thereon which are effective for actuating the button positioning and button transferring devices, are of such form and timing that they are without action on the above named 60 mechanisms during the time of the sewing of the button through the holes thereof onto the fabric and when the presser foot is lowered down onto the fabric below the level or plane at which the button is positioned, or 65 has its eyes brought around to the longitudi-

nal alinement, and at which time the transfer of the button into the presser foot is performed; and the cams referred to in this paragraph in the period after the completion of the button sewing-on action 70 comparatively quickly effect the operation required of them and then pass around out of engagement with the devices with which they coact during the greater part of the cycle of operation.

It will be noted that in this machine, and as may be perceived from the drawings, the gearing connections between the shaft H^2 which drives the mechanism which actuates and controls the button positioning and 80 transferring mechanism, as compared with the gearing which drives the mechanism having to do with the sewing operations is such that there may be a considerable number of sewing operations as necessary for 85 the proper stitching of the button onto the fabric while the cam shaft J is making but a single rotation.

As represented in Fig. 11, the crank stud n^2 on the face of the rotary wheel n^3 is made 90 radially adjustable whereby the shifting stroke of the presser foot and throat plate, which moves forwardly and rearwardly in unison may be nicely regulated to accord with differences of distance between eyes of 95 buttons which may be variously used as occasions may require.

The manner in which duplicate sets of the mechanism, which mainly have been herein described for one complete button-positioning, feeding, and sewing machine, are organized by the employment of some principal parts in common is apparent from an inspection of the drawings; and in practice the machine is to be made with as many 100 duplications of the mechanisms as will correspond with the number of buttons to be simultaneously sewed onto a piece of fabric, all, of course, as would be manifest to one skilled in the art.

I claim:—

1. In a machine of the character described, sewing means comprising stitch forming mechanism and a button receiving and holding presser foot and throat plate which foot 115 and plate are horizontally movable, and means for imparting movements thereto in unison, and feeding means comprising a positioning or eye-alining device and a device for transferring the button from the position in which it is alined to one within the presser foot.

2. In a machine of the character described, sewing means comprising stitch forming mechanism, a button receiving and holding 125 presser foot and a throat plate, which foot and plate are horizontally movable, and which presser foot is vertically movable, means for imparting the stated movements to said foot and plate, and feeding mecha- 130

150

6
nism comprising a positioning or eye-aligning device, and a device for transferring the button to within the presser foot located at a level above the throat plate and up to 5 which the presser foot is adapted to be raised.

3. In a machine of the character described, the combination with a mechanism for sewing a button onto a fabric, of mechanism for feeding the button to its position to be sewed comprising a button chute, a button receiver to which the chute leads, a rotative finder, yieldingly supported, having an upstanding eccentrically located pin 10 to engage in an eye of a button, means for upwardly moving the finder whereby the pin thereof may be brought to bearing against the bottom of the button, means for rotatively moving the finder whereby its pin may register with, and then upwardly 15 engage into, the eye of the button, means for limiting the extent of the rotative movement of the finder while in engagement with the button, and means for transferring the eye aligned button from the receiver to the 20 position at which it is to be sewed.

4. In a machine of the character described, the combination with a mechanism for sewing a button onto a fabric; of mechanism for feeding the button to its position to be sewed comprising a button receiver, and means for supplying buttons thereinto; a rotative finder upwardly spring pressed, having an upstanding eccentrically located 30 pin to engage in an eye of a button; finder actuating mechanism comprising means for upwardly moving the finder so that the pin thereof may bear against the bottom of the button, means for rotatively moving 35 the finder whereby its pin may register with and upwardly engage into the eye of the button; means for limiting the extent of the rotative movement of the finder while in engagement with the button;—said finder 40 actuating mechanism being operable to downwardly withdraw the finder from proximity with the button, and means for transferring the eye aligned button from the receiver to the position at which it is to be sewed.

5. In a machine of the character described, the combination with a mechanism for sewing a button onto a fabric; of mechanism for feeding the button to its position to be sewed comprising a button receiver, and means for supplying buttons thereinto; a rotative finder upwardly spring pressed, having an upstanding eccentrically located pin to engage in an eye of a button; finder 55 actuating mechanism comprising means for upwardly moving the finder so that the pin thereof may bear against the bottom of the button, means for rotatively moving the finder whereby its pin may register with and upwardly engage into the eye of the button; 60

means for limiting the extent of the rotative movement of the finder while in engagement with the button;—said finder actuating mechanism being operable to downwardly withdraw the finder from proximity with the button, means for also preventing the rotation of the finder while the latter is being withdrawn, and means for transferring the eye aligned button from the receiver to the position at which it is to be sewed. 70

6. In a machine of the character described, the combination with a mechanism for sewing a button onto a fabric, of mechanism for feeding the button to its position to be sewed comprising a button chute, a button receiver to which the chute leads, a rotative finder yieldingly mounted having an upstanding eccentrically located pin to engage in an eye of a button, means for upwardly moving the finder to cause said pin to bear against the bottom of the button, means for rotatively moving the finder whereby its pin may register with and upwardly engage into the eye of the button, means for limiting the extent of the rotative movement of the finder while in engagement with the button, and means for transferring the eye aligned button from the receiver to the position at which it is to be sewed. 80

7. In a machine of the character described, the combination with a button-sewing mechanism, of a button receiver and means for feeding buttons thereinto, a rotative finder comprising a vertical shaft provided with a head having an eccentrically located upstanding pin under the button receiver, a sleeve through which said shaft is journaled, a spring reacting upwardly against the finder, a spring upwardly reacting against the sleeve, a stop member on the sleeve and a stop member on the finder shaft adapted for a rotation limiting engagement one with another, a device for imparting a vertical movement to the sleeve and finder engaged thereby and to subsequently cause a lowering of such parts, means for imparting rotative movement to the finder shaft and means for transferring the finder positioned button from the receiver to the position at which it is to be sewed. 90

8. In a machine of the character described, in combination, a button receiver, a presser foot adapted for the reception and retention of a button, and a slide in alinement with the receiver and presser foot, of a shaft adapted for rotation and also for a vertical movement having a button finder at its upper end below the button receiver, a pivoted lever and means with which it coacts for controlling the vertical movement of the finder shaft, a cam lever coacting with the first named lever and with said slide, and means for imparting a swinging reciprocal movement to said cam lever. 100

9. In a machine of the character described, in combination, a button holding presser foot, a button receiver and a slideway in alinement with the foot and receiver, a rock-shaft having an extension arm and a lever carried by said rockshaft and connected with the slideway, a thrust rod coacting with said arm and a revoluble cam for imparting endwise movement to the thrust rod and a swinging of the lever in one direction and a retracting spring for said lever.
10. In a machine of the character described, the combination with the sewing machine head, of a slide longitudinally and horizontally movable thereon, a button receiving and holding presser foot and a spring arm connecting the same to the slide, means for horizontally and longitudinally reciprocating the slide and means for periodically vertically moving the presser foot as permitted under the flexure of its spring carrying arm.
11. In a machine of the character described, in combination, the sewing machine head, a slide horizontally and longitudinally movable thereon, a spring arm carried by the slide, a button receiving presser foot carried by the spring arm, means for reciprocating the slide in one period of operation and cam actuated means for imparting vertical movement to the presser foot carrying spring arm in another period of operation.
12. In a machine of the character described, stitch forming mechanism, and a reciprocatory presser foot, a shaft, and operating connections between such shaft and the stitch forming mechanism and reciprocatory presser foot for actuating the stitch forming mechanism and moving the presser foot, button feeding means and button positioning and button transferring mechanisms, and automatic mechanism for rotatively driving one of said shafts and currently therewith driving the other of said shafts, and for thereafter ceasing to drive one shaft and then only driving the other shaft.
13. In a machine of the character described, stitch forming mechanism, and a reciprocatory presser foot, a shaft and operating connections between such shaft and the stitch forming mechanism and reciprocatory presser foot for actuating them, button feeding means, and button positioning and button transferring mechanism, and a shaft provided with a cam for controlling the action of said positioning and transferring mechanism, and a shaft and operating connections between it and the cam shaft for causing a rotation of the latter, automatic mechanism for rotatively driving the said shaft which operates the cam shaft, and sewing mechanism actuating shaft in unison and for thereafter ceasing to drive the last named shaft and then only driving the shaft which operates the cam shaft.
14. In a machine of the character described, mechanism appurtenant to the sewing operation, and mechanism appurtenant to button positioning and transferring mechanism, a shaft in actuating connection with the sewing mechanism, a cam provided shaft actuating the positioning and transferring mechanisms, a driving shaft for the cam provided shaft, means for causing from a temporary rotative driving of the sewing mechanism shaft a partial rotation of the cam driving shaft, and means for causing a discontinuance of the driving of the sewing mechanism shaft and a completion of the rotation of the cam driving shaft.
15. In a machine of the character described, sewing mechanism and button positioning and transferring mechanism, a cam, controlling the positioning and transferring mechanism and a rotary shaft for operating said cam, another shaft for actuating the sewing mechanism, means for driving both said shafts in unison, means for discontinuing driving action of the sewing mechanism shaft, but continuing the driving of the cam driving shaft, and automatic means for the stoppage of the cam driving shaft.
16. In a machine comprising sewing mechanism, and button positioning and transferring mechanism, a shaft in actuating connection with the sewing mechanism, a cam shaft having a cam for actuating the positioning and transferring mechanism, a driving shaft for the cam shaft, means for causing from the rotation of the sewing mechanism shaft a corresponding rotative movement of the cam driving shaft, and means for causing a discontinuance of the rotation of the sewing mechanism shaft and a completion of the rotation of the cam driving shaft.
17. In a machine of the character described, sewing mechanism and button positioning and transferring mechanisms, a cam controlling the positioning and transferring mechanism and a rotary shaft for operating said cam, another shaft for actuating the sewing mechanism, and means for driving both said shafts in unison, automatic means for discontinuing the driving of the sewing mechanism shaft, but operative for continuing the driving of the cam shaft, and finally stopping the driving of the cam shaft.
18. In a machine of the character described, sewing mechanism and button positioning and transferring mechanism, a shaft actuating the sewing mechanism, and another shaft for controlling and imparting the movements to the positioning and transferring mechanism, each said shaft having a pulley thereon, engagement means between

- said pulleys whereby one causes the rotation of the other, a belt adapted to have running engagement around one of the pulleys to thereby rotate its shaft and also the pulley 5 of the other shaft, and automatic means for the shifting of said belt from the one pulley to the other for the positive driving of the latter and to leave the one from which it was shifted inactive.
- 10 19. In a machine of the character described, sewing mechanism, and button positioning and transferring mechanism, a tubular shaft having driving connection with the sewing mechanism and provided 15 with a pulley having a cam inclined face terminating in a shoulder, another shaft extended through the tubular shaft, having actuating and controlling connections with the positioning and transferring mechanisms and having a pulley alongside the 20
- first named pulley and provided with a spring pressed stud, a belt adapted to have running engagement around the first named pulley for positively driving it, and, through the engagement of the shoulder thereof with 25 said stud, driving the second named pulley, automatic means for causing a shifting of said belt from the first onto the second pulley and causing the positive stoppage of the rotative movement of the first one, and 30 automatic means for causing at a predetermined time the positive stopping of the second pulley.
